Primary Examiner — Robert M Spear*Assistant Examiner* — Darcey E Heflin*(74) Attorney, Agent, or Firm* — Reinhart Boerner Van Deuren P.C.**(57) CLAIM**

We claim the ornamental design for a filter closure, as shown and described.

DESCRIPTION

FIG. 1 is a top perspective view of a filter closure;
FIG. 2 is a top view of the claimed design of FIG. 1;
FIG. 3 is right side view of the claimed design of FIG. 1, the left side view being a mirror image thereof;
FIG. 4 is a front view of the claimed design of FIG. 1;
FIG. 5 is a back view of the claimed design of FIG. 1;
FIG. 6 is a bottom view of the claimed design of FIG. 1;
FIG. 7 is a bottom perspective view of the claimed design of FIG. 1; and,
FIG. 8 is a bottom perspective view from an opposite side from FIG. 7 of the claimed design of FIG. 1.
In the drawings, the broken lines depict environmental subject matter only that forms no part of the claim.
